CLAIM

The ornamental design for a horticulture light fixture, as shown and described.

DESCRIPTION

FIG. 1 is a left perspective side view;

FIG. 2 is a front view;

FIG. 3 is right perspective side view;

FIG. 4 is a bottom view;

FIG. 5 is a bottom perspective view;

FIG. 6 is a right view; and,

FIG. 7 is a top view.

The broken lines showing the reflector in FIGS. 4 and 5 are for the purpose of illustrating unclaimed portions of the article and form no part of the claimed design.
